UNITED STATES PATENT OFFICE.

ROBERT C. DANLY, OF CHICAGO, ILLINOIS, ASSIGNOR TO LUDWIG & LUDWIG, OF CHICAGO, ILLINOIS, A CORPORATION OF ILLINOIS.

DRUM AND THE LIKE.

1,356,193.

Specification of Letters Patent. Patented Oct. 19, 1920.

Application filed November 28, 1919. Serial No. 341,036.

To all whom it may concern:

Be it known that I, ROBERT C. DANLY, a citizen of the United States of America, and a resident of Chicago, in the county of Cook, 5 State of Illinois, have invented certain new and useful Improvements in Drums and the like, of which the following is a specification.

This invention relates to that class of 10 tuning mechanism for musical instruments in which the tension or tone of sound producing membrane is adapted for ready regulation by the player, an example of which constitutes the subject matter of Letters Patent No. 1,054,009, issued February 15 25, 1913, to William F. Ludwig, and the present improvement has for its object:

To provide a structural formation and association of parts adapted to impose a uniform 20 outward tensioning stress upon the sound producing membrane of a musical instrument in a simple and effective manner, and in which the required initial and main tensioning stresses on said membrane can 25 be readily effected and maintained, and with which the adjusting means can be fastened at any desired point in its adjustment in an effective manner and capable of ready release by the operator, all as will herein- 30 after more fully appear. In the accompanying drawings:—

Figure 1, is an elevation, with parts in section, illustrating the preferred construction of the invention as applied to a kettle 35 drum.

Fig. 2, is a detail elevation of the windlass drum of the mechanism.

Fig. 3, is a top view of the kettle drum and mechanism.

40 Fig. 4, is a detail elevation of one of the primary claw or shackle bars of the membrane tensioning means.

Fig. 5, is a detail elevation of the carriage or spider of the windlass drum above referred to.

Fig. 6, is a detail sectional elevation of the lower portion of the kettle drum, supporting frame and mechanism, in a plane at right angles to the plane of Fig. 1.

50 Fig. 7, is an enlarged detail side elevation of the windlass drum and carriage above referred to.

Fig. 8, is a sectional plan view of line 8—8, Fig. 1, of the universal joint which

connects the drum carrying spider with the 55 supporting frame of the instrument.

Fig. 9, is a detail top view of the supporting frame, with parts of the mechanism in place, and with parts of the mechanism removed.

Fig. 10, is a detail plan of the multiple sheave head which forms the intermediate connection between the main tension number and the series of radial secondary tension numbers of the mechanism.

Fig. 11, is a detail section on line 11—11, Fig. 10.

Like reference numerals indicate like parts in the several views.

Referring to the drawings, 1 designates 70 the main shell or body of a drum or like musical instrument, of any usual and suitable form, the opening of which is closed by the usual resonating head or membrane 2 which is stretched over a rounded rim or 75 margin of said opening. To such end the margin of the head or membrane 2 is attached in any usual manner to an adjustable straining hoop or ring 3 fitting and moving outside the main shell or body 1 as 80 shown.

4 designates a circularly spaced series of claw or shackle hooks having engagement at their upper ends with the ring or hoop 3 aforesaid, through adjustable bearing 85 screws 5, which permit of individual adjustment of the instrument. The claw or shackle hooks 4 are connected to the shell or body 1 in an adjustable manner by means of a series of individual pull cords or connections 6, which are operatively connected to a common means for effecting a simultaneous pull on the entire series of cords or connections 6. The scope of this part of the invention embraces any usual and suitable 95 means for effecting the above mentioned simultaneous pulling action on the series of cords or connections 6, the preferred construction and association of parts as shown in the drawings comprises parts and structures as follows:—

7, designates a series of bearing sheaves journalled on the exterior of the main shell or body 1, and around which the series of cords or connections 6 pass and extend into 105 the interior of the shell or body 1 in the radial manner shown in Figs. 1 and 3.

8 designates a central connecting head or

spider to which the inner ends or terminals of the series of cords or connections 6 are attached, preferably by a twin or loop formation of each cord 6 having engagement 5 around an individual sheave or pulley 9. In the specific construction shown in Figs. 10 and 11, the head or spider 8 consists of upper and lower disks between which the series of sheaves 9 are journaled as shown. 10 The said disks are held in proper spaced relation by an interposed washer 10, and are held in proper assembled relation by the nut 11 and screw-threaded shank of a pulley housing 12, as shown more particularly in 15 Fig. 11.

13 designates a sheave or pulley journaled in the aforesaid pulley housing 12 and adapted to receive the upper end of the main pull cord or connection 14 of the mechanism. Said main pull cord or connection 14 is preferably of the same twin or loop form as the series of pull cords or connections 6 above described, and at its other end the main cord or connection 14 is attached 20 to an operating mechanism, hereinafter described in detail.

With the arrangement of the series of pull cords or connections 6 and main pull cord or connection 14 as above described, a 30 downward pulling stress on the main cord 14, with a corresponding downward movement of the connecting head or spider 8, will move the inner portions of the pull cords 6 from their normal horizontal position shown in Fig. 1, to an inclined position with an individual movement of each pull cord 6 along its length, adapted to impose a very powerful tensioning stress upon the drum head or membrane 2 aforesaid.

40 15 designates the usual carrying spider for the drum shell or body 1, and in the present structure is formed with a central tubular hub 16, adapted to fit and have supporting engagement with a tubular vertical stud or trunnion on the upper end of the 45 hereinafter described universal joint connection, so that the drum shell or body 1 and its carrying spider 15 are capable of a turning adjustment in a horizontal plane.

50 17 designates the supporting frame or floor base of the mechanism, which in the preferred form shown in the drawings comprises a tubular vertical sleeve or member 17', a fixed longitudinal bar on foot 18, and a pair of lateral feet or members 19 preferably of the hinged or folding type shown in Figs. 1 and 6.

20 designates vertical track rails secured to the frame 17 and forming guides for the 60 vertically moving carriage 21 of the tensioning mechanism of the main pull cord 14 aforesaid. In the preferred construction shown in Figs. 5 and 7, the carriage 21 is provided with track wheels 22 and with

journal orifices for the windlass drum now 65 to be described.

23 designates the primary tensioning windlass or drum, journaled in the carriage 21 aforesaid, and provided with an operating handle or key 24 and with a ratchet rim 70 25 adapted for engagement with a spring pawl 26 on the carriage, so as to be locked at any required turning adjustment to which the said windlass or drum 23 may have been moved by its key or handle 24 aforesaid. 75 The lower end of the main pull cord 14 is attached to and winds upon the said windlass or drum 23, and the above described adjusting means provides for an initial tensioning stress upon said main pull cord 14, 80 and for a change in such initial stress as the judgment of the player may suggest.

27 designates a longitudinally extending operating foot lever formed with a short angularly disposed extension or arm 85 28 which is pivoted at its upper end between pivot brackets 29 on the tubular sleeve 17' of the supporting frame 17 aforesaid. The arm 28 constitutes one member of a toggle structure, the other member or link 30 of 90 which is pivotally connected at one end to the arm 28 at its point of juncture with the foot lever 27, while the other end of the link 30 is pivotally connected to the carriage 21 aforesaid. With the above described construction a downward movement of the foot lever 27 causes a straightening movement of the aforesaid toggle members, which in turn imparts a very powerful downward movement to the carriage 21 and main pull cord 14 to attain the required degree of tension stress on the drum head or membrane 2. 95

31 and 32 designates a pair of circular pivot ears or heads adapted for surface frictional engagement and constituting a portion of the aforesaid universal joint or connection between the drum carrying spider 15 and the supporting frame 17' of the instrument. In the present construction the heads 31, 32 are located to one side of the 110 vertical center of the instrument, in order to admit of a clear passage for and movement of the main pull cord 14.

33 designates a stud bolt passing centrally through the pivot ears 31, 32, and 115 having an adjusting nut at one end by means of which the frictional holding stress between said pivot ears is regulated.

34 designates an idler sheave carried by the stud bolt 33 for guiding engagement 120 with the main pull cord 14, as shown in Figs. 1, 6, and 8.

35 designates a curved bracket piece forming a fixed part of the pivot ear 31 aforesaid, and having a round and horizontally 125 disposed stem or trunnion 36 adapted for turning engagement in the connecting piece or trunk now to be described.

37 designates a vertical stem forming a part of the connecting piece or trunk above referred to, and adapted to fit and have vertical adjustment in the sleeve portion 17' 5 of the supporting frame 17 aforesaid. The stem 37 is held to its vertical adjustment by a clamping bolt 38 passing through bracket ears at the sides of a vertical slit in the sleeve 17', as shown more particularly in 10 Figs. 1 and 9.

39 designates a split sleeve forming a part of the stem 37 aforesaid, and disposed in a horizontal direction at the upper end of said item 37. Said sleeve 39 receives the 15 stem or trunnion 36 aforesaid, and is adapted to hold said stem in its different turning adjustment by a clamping bolt 40 passing through bracket ears at the side of the slit in said sleeve 39.

41 designates a tubular vertical trunnion constituting a fixed part of the pivot ear 32 aforesaid, and adapted for engagement with the central tubular hub 16 of the drum carrying spider 15 heretofore described, and 25 with its bore adapted to receive and afford a free passage for the main pull cord 14. With the above described formation and association of parts, a universal adjustment of the instrument to bring its head or 30 membrane 2 to any plane which the player may desire, can be readily and effectively made.

42 designates an upright segmental holding bar or rod having fixed attachment at 35 its lower end to the longitudinal foot 18 of the supporting frame 17, and passing through an orifice or passage formed therefor in the foot lever 27 aforesaid.

43 designates a cramp piece or bar pivoted at one end to the foot lever 27 and having a central orifice encircling the holding bar 42 aforesaid. In its raised position in right angle relation to the rod 42, said cramp piece 43 is adapted to permit a free 45 movement upon said rod 42, while in its depressed position in oblique relation to the rod 42. Said cramp piece is adapted to bind the sides of its central orifice upon the rod 42 to prevent any independent movement 50 between the parts and attain a locking of the foot lever 27, at any desired adjustment.

44 designates a spring tending to yieldingly maintain the cramp piece 43 in the oblique and engaging position above described.

45 designates a rock lever pivoted on the foot lever 27 with one end adapted for manual operation, while the other end has engagement beneath the cramp piece 43 and 60 adapted to lift the same into the raised and disengaged position above described.

46 designates an abutment collar adjustably attached to the rod 42 and adapted in a final downward movement of the foot 65 lever 27 to contact with the cramp piece 43

and automatically move the same into the disengaged position above described.

Having thus fully described my said invention what I claim as new and desire to secure by Letters Patent is:—

1. In a musical instrument of the type described, a supporting frame, a shell or body mounted on said frame, a membranous head therefor, a rigid border rim carrying said head, a series of primary pull connections 70 associated with said rim, a main pull connection common to series of pull connections, a vertically movable carriage connected to said main pull connection, and a foot lever pivoted to the supporting frame and operatively connected to said carriage.

2. In a musical instrument of the type described, a supporting frame, a shell or body mounted on said frame, a membranous head therefor, a rigid border rim carrying said head, a series of primary pull connections 85 associated with said rim and connected in common to a centrally disposed head, a main pull connection attached to said central head, a vertically movable carriage connected 90 to said main pull connection, and a foot lever pivoted to the supporting frame and operatively connected to said carriage.

3. In a musical instrument of the type described, a supporting frame, a shell or body, 95 mounted on said frame, a membranous head therefor, a rigid border rim carrying said head, a series of primary pull connections associated with said rim and connection in common to a centrally disposed head, a main 100 pull connection attached to said central head, a vertically movable carriage connected to said main pull connection, and a foot lever pivoted to the supporting frame and operatively connected to said carriage, each primary pull connection being of a loop form 105 and attached to the central head by a connecting sheave.

4. In a musical instrument of the type described, a supporting frame, a shell or 110 body mounted on said frame, a membranous head therefor, a rigid border rim carrying said head, a series of primary pull connections attached to said rim by a series of hooks having individually adjustable bearing screws, a main pull connection common to the series of pull connections, a vertically movable carriage connected to said main pull connection, and a foot lever pivoted to the supporting frame and operatively connected to said carriage.

5. In a musical instrument of the type described, a supporting frame, a shell or body mounted on said frame, a membranous head therefor, a rigid border rim carrying said head, a series of primary pull connections attached to said rim by a series of hooks having individually adjustable bearing screws, 125 said primary pull connections being connected in common to a central head, a main pull 130

connection attached to said central head, a vertically movable carriage connected to said main pull connection, and a foot lever pivoted to the supporting frame and operatively connected to said carriage.

6. In a musical instrument of the type described, a shell or body, a membranous head therefor, a rigid border rim carrying said head, a series of primary pull connections associated with said rim, a main pull connection common to the series of pull connections, a supporting frame for the instrument body, a carriage having vertical movement on said frame and connected to the main pull connection, a foot lever pivoted to said frame, and a toggle link connecting said lever to said carriage.

7. In a musical instrument of the type described, a shell or body, a membranous head therefor, a rigid border rim carrying said head, a series of primary pull-connections associated with said rim, a main pull connection common to the series of pull connections, a supporting frame for the instrument body, a carriage having vertical movement on said frame and connected to the main pull connection, a foot lever pivoted to said frame, a toggle link connecting said lever to said carriage, and means for locking said lever at any desired adjustment.

8. In a musical instrument of the type described, a shell or body, a membranous head therefor, a rigid border rim carrying said head, a series of primary pull connections associated with said rim and connected in common to a centrally disposed head, a main pull connection attached to said central head, a supporting frame for the instrument body, a carriage having vertical movement on said frame and connected to the main pull connection, a foot lever pivoted to said frame, and a toggle link connecting said lever to said carriage.

9. In a musical instrument of the type described, a shell or body, a membranous head therefor, a rigid border rim carrying said head, a series of primary pull connections associated with said rim and connected in common to a centrally disposed head, a main pull connection attached to said central head, a supporting frame for the instrument body, a carriage having vertical movement on said frame and connected to the main pull connection, a foot lever pivoted to said frame, a toggle link connecting said lever to said carriage, and means for locking said lever at any desired adjustment.

10. In a musical instrument of the type described, a shell or body, a membranous head therefor, a rigid border rim carrying said head, a series of primary pull connections associated with said rim, a main pull connection common to the series of pull connections, a supporting frame for the instrument body, a carriage having vertical move-

ment on said frame, a revoluble windlass mounted on said carriage and having attachment with the main pull connection, a pawl and ratchet mechanism associated with said windlass, a foot lever pivoted to said frame, and a toggle link connecting said lever to said carriage.

11. In a musical instrument of the type described, a shell or body, a membranous head therefor, a rigid border rim carrying said head, a series of primary pull connections associated with said rim, a main pull connection common to the series of pull connections, a supporting frame for the instrument body, a carriage having vertical movement on said frame, a revoluble windlass mounted on said carriage and having attachment with the main pull connection, a pawl and ratchet mechanism associated with said windlass, a foot lever pivoted to said frame, a toggle link connecting said lever to said carriage, and means for locking said lever at any desired adjustment.

12. In a musical instrument of the type described, a shell or body, a membranous head therefor, a rigid border rim carrying said head, a series of primary pull connections associated with said rim and connected in common to a centrally disposed head, a main pull connection, attached to said central head, a supporting frame for the instrument body, a carriage having vertical movement on said frame, a revoluble windlass mounted on said carriage and having attachment to the main pull connection, a pawl and ratchet mechanism associated with said windlass, a foot lever pivoted to said frame, and a toggle link connecting said lever to said carriage.

13. In a musical instrument of the type described, a shell or body, a membranous head therefor, a rigid border rim carrying said head, a series of primary pull connections associated with said rim and connection in common to a centrally disposed head, a main pull connection attached to said central head, a supporting frame for the instrument body, a carriage having vertical movement on said frame, a revoluble windlass mounted on said carriage and having attachment to the main pull connection, a pawl and ratchet mechanism associated with said windlass, a foot lever pivoted to said frame, a toggle link connecting said lever to said carriage, and means for locking said lever at any desired adjustment.

14. In a musical instrument of the type described, a shell or body, a membranous head therefor, a rigid border rim carrying said head, a series of primary pull connections associated with said rim, a main pull connection common to the series of pull connections, means for imposing a pulling stress on said main connection, and a supporting frame adjustably connected to the instru-

ment body by a universal coupling having pivot ears arranged to one side of the vertical axis of the revolute connection of said coupling with the instrument body.

- 5 15. In a musical instrument of the type described, a shell or body, a membranous head therefore, a rigid border rim carrying said head, a series of primary pull connections associated with said rim and connected
10 in common to a centrally disposed head, a main pull connection attached to said central head, means for imposing a pulling stress on said main connection, and a supporting frame adjustably connected to the instrument body by a universal coupling having 45
15 pivot ears arranged to one side of the vertical axis of the revolute connection of said coupling with the instrument body.
16. In a musical instrument of the type
20 described, a shell or body, a membranous head therefor, a rigid border rim carrying said head, a series of primary pull connections associated with said rim and connected in common to a centrally disposed head, a
25 main pull connection attached to said central head, means for imposing a pulling stress on said main connection, each pull connection being of a loop form and attached to the central head by a connecting
30 sheave, and a supporting frame adjustably connected to the instrument body by a universal coupling having pivot ears arranged to one side of the vertical axis of the revolute connection of said coupling with the
35 instrument body.
17. In a musical instrument of the type described, a shell or body, a membranous head therefor, a rigid border rim carrying said head, a series of primary pull connec-
40 tions attached to said rim by a series of shackle hooks having individually adjust-

able bearing screws, a main pull connection common to the series of pull connections, means for imposing a pulling stress on said main pull connection, and a supporting 45 frame adjustably connected to the instrument body by a universal coupling having pivot ears arranged to one side of the vertical axis of the revolute connection of said coupling with the instrument body. 50

18. In a musical instrument of the type described, a shell or body, a carrying spider for the said body provided with a central hub, a supporting frame, and a universal coupling between said spider and frame, 55 said coupling having a vertical tubular trunnion engaging the hub of the spider and pivot ears arranged to one side of the vertical axis of said trunnion.

19. In a musical instrument of the type 60 described, a shell or body, a carrying spider for said body, a supporting frame, and a universal coupling, one member of which is attached to the aforesaid spider and the other member of which is attached to the 65 aforesaid frame, said coupling having a central passage.

20. In a musical instrument of the type described, a supporting frame, a shell or body mounted on said frame, a membranous 70 head therefor, a rigid border rim carrying said head, a series of primary connections, associated with said rim, a main operative connection common to the series of primary connections, a movable carriage having ad- 75 justable attachment to said main operative connection, and a foot lever operatively connected to said movable carriage.

Signed at Chicago, Illinois, this 24th day of November, 1919.

ROBERT C. DANLY.
